(57) **CLAIM**

The ornamental design for a toy as shown and described.

DESCRIPTION

FIG. 1 is a perspective view of a toy showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof; and,

FIG. 9 is an enlarged view of a portion of the toy taken along the dash-dot-dash line in FIG. 2.

The broken lines depict portions of the toy and form no part of the claimed design.

1 Claim, 9 Drawing Sheets
